SOAP DISPENSER

Herbert W. Smith, West Newton, Mass., assignor,
by mesne assignments, to Bostonia Products
Co., Boston, Mass., a corporation of Massa-
chusetts

Application February 6, 1936, Serial No. 62,615

7 Claims. (Cl. 221—79)

This invention relates to dispensers for soap or like products in semi-liquid or paste form and has for its primary object the production of a device of this nature which will be relatively simple in construction, substantially automatic in operation, and generally more efficient than like devices heretofore known.

The product to be dispensed is packed and sold in containers, such as cylindrical cans, having one end closed by a removable cover and the other end provided with an exit passage closed by a stopper. The dispenser is constructed readily and conveniently to receive the open end of the container when the cover is removed therefrom and is also provided with a valve which serves normally to close the exit passage, it being understood that the stopper is removed when the container is applied to the dispenser. The dispenser furthermore includes a piston arranged to fit the interior of the container and adapted to be moved inwardly thereof to extrude a small quantity of the soap from the exit passage preferably upon movement of a handle provided on the dispenser. The exit passage is normally closed by the valve, the valve being automatically withdrawn upon movement of the handle.

As above stated, one object of the invention is to provide a dispenser of the herein described type which will be substantially automatic in operation and at the same time relatively simple and efficient. To that end, the device preferably embodies a single handle and means cooperating therewith for both withdrawing the valve and forcing the piston inwardly of the container upon the movement of the handle. The withdrawal of the valve permits the discharge of a quantity of soap from the exit passage and the inward movement of the piston forces the contents of the container toward such passage, the user of the device thus serving the entire operation merely by moving the handle. The dispensing operation is entirely automatic throughout the dispensing of the entire contents of the container, and relatively simple and convenient means is provided to permit easy removal of the empty container and the substitution of a full container therefor.

These and other features of the invention will be best understood and appreciated from the following description of a preferred embodiment thereof, selected for purposes of illustration and shown in the accompanying drawing in which,—

Fig. 1 is a plan view of the dispenser,

Fig. 2 is in side elevation, partially in section,
Fig. 3 is a transverse sectional view, taken on
the line 3—3 of Fig. 2,

Fig. 4 is a vertical sectional view therethrough.

In the drawing 10 indicates a body member comprising two pieces having an end wall 11 and annular flanged portions secured together at 12, a similar annular flanged portion depending downwardly therefrom at 14. A bushing 16 is headed centrally into the end wall at 17 and mounted within the bushing is a tube 18 having its downwardly extending portion threaded at 20. The tube is rotatable within the bushing 16 and is supported therein by a bushing 22 having a reduced portion threaded into the upper end of the tube, a spring washer 24 being interposed between the bushing and a ratchet wheel 26 fixed to the tube. A second ratchet wheel 28 is fixed to the tube below and in spaced relation to the bushing 16, the teeth on the ratchet wheels 26 and 28 being disposed respectively in opposite directions. The body member is slotted at 30 and an operating handle extends through this slot. This handle has a bifurcated hub portion 34 rotatably mounted on the tube 18 and embracing the ratchet wheel 28.

The flange portion 14 of the body member is adapted to receive thereover the open end of a cylindrical container 36 having a conical bottom portion 38 with a centrally disposed exit 40 therethrough. The container may be of metal or other suitable material adapted to hold semi-liquid soap or other product to be dispensed, the open end and exit port being closed by a cover and stopper while the product is being marketed which covering and stopper are adapted to be removed when the container is applied to the dispenser. A spring ring 42 carried within the flange 14 has two pins 44 thereon extending outwardly through the flange and adapted to engage within corresponding holes in the container to hold the container in place on the dispenser.

The port 40 is normally closed by a valve 46 on the bottom end of a rod 48 extending upwardly through the tube 18. The rod and valve are normally forced downwardly by gravity and by a spring 50 surrounding the rod between a collar 52 thereon and the bushing 22. A spring 54 on the bushing 16 normally holds the handle 50 in the position of full lines (Fig. 1) in which position the valve 46 closes the port 40. Movement of the handle toward the broken line position is adapted to raise the valve and simultaneously therewith move downwardly within the

container a piston 54 in threaded engagement with the tube 18 at 20. It will be apparent that this action serves to dispense a predetermined quantity of the product from the port 40. The 5 piston is moved through the action of a spring detent 58 carried by the handle and operating on the ratchet wheel 28 to rotate the tube forwardly with the handle and in a direction to move the piston downwardly. A spring detent 10 58 carried on the end wall 11 cooperates with the ratchet wheel 26 to prevent return rotation of the tube. The valve and rod are lifted by means of a cam 60 carried by a nut 64 threaded onto the top end of the rod. The other end of 15 this bracket extends downwardly through a hole 66 in the end wall 11 whereby to prevent rotation of the bracket.

The dispenser may be supported on a wall 68 by any suitable means, such as a bracket 70 20 spot welded to the body member at 72 and provided with holding screws 74 securing it to the wall.

Having thus described my invention, what I 25 claim as new and desire to secure by Letters Patent of the United States is,—

1. A dispenser for soap or the like, comprising a body having an annular portion adapted to receive the open end of a container, means for removably securing the container to said portion 30 whereby freely to suspend the container therefrom, a threaded tube suspended from the body through said annular portion, a piston threaded onto the tube and adapted to engage the interior wall of the container, a rod extending 35 through the tube and having a valve on its free end for cooperating with an exit in the container, a handle carried by the body and mounted for free pivotal movement on the tube, a ratchet wheel fixed to the tube, a detent carried by the handle and cooperating with the ratchet wheel to rotate the tube, and means including a cam carried by the handle for raising the rod and valve upon pivotal movement of the handle.

45 2. A dispenser for soap or the like, comprising a body having an annular portion adapted to receive the open end of a container, means for removably securing the container to said portion whereby freely to suspend the container therefrom, a threaded tube suspended from the body through said annular portion, a piston threaded onto the tube and adapted to engage the interior wall of the container, a rod extending 50 through the tube and having a valve on its free end for cooperating with an exit in the container, a handle carried by and having its inner portion housed within the body, the free end of the handle extending outwardly through a slot in the body wall, a spring normally holding the handle at one end of the slot, means for raising the rod and valve upon movement

of the handle against the action of the spring, means causing rotation of the tube and forward movement of the piston upon such movement of the handle, and means preventing reverse rotation of the tube upon return movement of the handle. 5

3. A dispenser for soap or the like, comprising a cap embodying an end wall and a flanged peripheral portion, an annular member having its top end fitting over and secured to said peripheral portion of the cap, a single walled cylindrical container having its top end open and fitted in overlapping relation on the bottom end of the member, means detachably securing the container to the member in such position whereby the container is suspended freely therefrom, a tube carried by the end wall and extending downwardly through the annular member, a piston on the tube for engaging the interior wall of the container, a rod within the tube and having a valve on its free end cooperating with a restricted exit in the container wall, and means including a handle carried by the cap and extending outwardly therefrom for raising the rod and valve and moving the piston longitudinally 20 along the tube. 25

4. The dispenser defined in claim 3 plus a cover housing the cap and parts carried thereby and having an edge portion removably fitting over the peripheral portion of the cap and substantially in abutting relation with the annular member. 30

5. The dispenser defined in claim 3 wherein the first-named means includes a spring ring within the interior of the annular member and having pins thereon extending outwardly through said member and engaging within openings through the container wall. 35

6. In combination, a single walled cylindrical container having an open top end and a conical bottom end with a centrally disposed exit port therethrough, a body member, means engaging the top end of the container freely and removably suspending the container from the body member, a threaded tube carried by the body member and disposed centrally within the container, a rod within the tube and having a valve at its free end cooperating with said port, a piston fitting within the container and threaded to the tube, means including a handle freely rotatable on the tube for raising the rod and valve upon movement of the handle and ratchet means for rotating the tube upon movement of the handle in one direction. 40 45

7. The combination set forth in claim 6 where- 50 in the valve normally closes the port when the handle is in its normal position, and a spring normally rotating the handle about the longitudinal axis of the tube to such position. 55
